UNITED STATES PATENT OFFICE.

JOHN J. MULVANEY, OF CINCINNATI, OHIO, ASSIGNOR OF THREE-FOURTHS TO CHARLES E. BABBITT AND JOHN L. BROWN, OF CINCINNATI, OHIO, AND HOWARD A. SUTTON, OF WYOMING, OHIO.

MACHINE FOR UNITING THE JOINTS OF SHEET-METAL PIPES.

SPECIFICATION forming part of Letters Patent No. 758,330, dated April 26, 1904.

Application filed September 2, 1902. Serial No. 121,833. (No model.)

To all whom it may concern:

Be it known that I, JOHN J. MULVANEY, a citizen of the United States, residing at Cincinnati, in the county of Hamilton and State of Ohio, have invented certain new and useful Improvements in Machines for Uniting the Joints of Sheet-Metal Pipes, of which the following is a full, clear, and exact description, reference being had to the accompanying drawings, forming part of this specification.

My invention relates to simple and efficient mechanism for uniting the joints of sheet-metal pipes, such as stovepipes, in a very secure manner and without the necessity of employing separate rivets and whereby the work can be done with great saving of time and but little expenditure of labor.

The novelty of my invention will be herein-after more fully set forth, and specifically pointed out in the claims.

In the accompanying drawings, Figure 1, Sheet 1, is a side elevation of a machine embodying my invention in one form of construction. Fig. 2, Sheet 1, is a corresponding view 25 of a machine embodying my invention under another form of construction. Fig. 3, Sheet 1, is an enlarged broken sectional detail of the blind-riveting dies. Fig. 4, Sheet 1, is a broken elevation of two united joints of pipe. Fig. 30 5, Sheet 2, is a side elevation of a machine embodying my invention under a further form of construction. Fig. 6, Sheet 2, is an end elevation of Fig. 5 looking from the left thereof. Fig. 7, Sheet 2, is an enlarged perspective of 35 a portion of pipe at its joint. Fig. 8, Sheet 2, is a corresponding view on the dotted line *xx* of Fig. 7.

The same letters of reference are used to indicate identical parts in all the figures.

40 My machine is designed especially for blind-riveting the joints of sheet-metal pipes, such as stovepipes, both on the longitudinal joints of each section and circumferentially around the pipe where two joints are telescopically united. In its simplest form (illustrated in Figs. 1 and 3) it consists of a mandrel or anvil *A*, having an exterior curvature in cross-section approximating that of the joint of pipe which

is slipped over it. This anvil or mandrel is secured at one end to any suitable support, as 50 the edge of a table or bench *B*, its opposite end being unsupported to permit the section of pipe represented by the dotted lines to be slipped over it.

Projecting up from the inner end of the 55 mandrel and in this instance secured thereto is a bracket-support *C*, with a socket-piece *D* extending over the top of the mandrel, and suitably guided in said socket-piece is a head or plunger *E*, whose lower end either has 60 secured to it or formed in it a hemispherical recess *d* to form a female die.

The upper end of the plunger *E* is shown engaged by a lever *F*, weighted at its rear end by a weight *G* and provided at its forward 65 end with an operating-handle *H* for reciprocating the plunger, and the lever itself is pivoted, as at *z*, to ears on the bracket *C*. Instead of the handpiece *H* and weight *G* the lever may be actuated by crank or cam mechanism driven by power, as indicated by the dotted lines.

The top of the mandrel has a perforation *f*, in which is confined the male die *a*, whose upper surface, projecting above the top of the 75 mandrel, comes directly under the female die *d*.

In operation the section of pipe *g*, with its longitudinal meeting edges bent in and interlocked after the manner usual in connecting pipe-sections, is first slipped upon the mandrel, and these interlocked meeting edges (indicated at *i*, Figs. 7 and 8) are hammered down. Then the ends of the pipe are successively slipped over the male die *a* and subjected to the action of the female die, which 85 blind-rivets the joint, as seen at *j*, which prevents any slipping longitudinally at the joint and forms a secure lock for the section of pipe.

In Fig. 2 I have shown the mandrel as considerably elongated and disposed transversely 90 to the bracket *C*, which is arranged at about the center of the mandrel. The ends of the mandrel are supported on brackets *I* by dowels *k*, so that either end may be lifted to slip on or off a section of pipe. Two sections 95 which have been blind-riveted on their longi-

tudinal seams can have their ends telescopically united, as seen in Fig. 4, and then by subjecting such joint to the action of the dies and rotating the sections upon the mandrel they 5 will be blind-riveted together, as at *l*. Then when it is desired to unite a large number of sections it is only necessary to support the mandrel at one end, leaving the same long enough to hold two sections at a time, with 10 room to shift them for all the operations necessary to be performed upon them.

In Figs. 5 and 6 I have shown what I consider the most perfect form of construction of a machine embodying my invention. Here 15 the mandrel is supported only at one end, as in Fig. 1, and there are slotted guides *C*² at each end thereof, in the slots whereof are confined the ends of a cross-head *B*², having a reciprocal vertical movement given to it by a 20 rope *L*, passed over a puller *M*, with its end attached to the middle of the cross-head, or by any other suitable actuating mechanism. The cross-head in this instance forms the hammer for uniting the longitudinal seams *i* of the 25 pipe-sections, while at the same time it coacts with the mandrel and the male die thereon in doing the blind-riveting. The female die in this case (indicated at *b*²) is simply a hemispherical recess on the under surface of the 30 cross-head *B*², and there may be a number of these recesses, as indicated by dotted lines,

and a corresponding number of apertures in the mandrel directly under them for the reception of one or more male dies *a* to suit the character of the work to be done, as will be 35 readily understood.

Having thus fully described my invention, I claim—

1. In a machine of the character described, the combination of a horizontal mandrel free 40 at one end to permit one or more sections of sheet-metal tubing to be slipped over the same, a male die secured thereto and projecting therefrom, a vertically-reciprocating cross-head above and coacting with said mandrel, 45 supports for said cross-head, and a female die, on the under side of said cross-head, arranged over said male die, substantially as described and for the purpose specified.

2. The herein-described machine consisting 50 of the horizontal mandrel *A*, the cross-head *B*, the slotted guide-supports *C*² for said cross-head, means for vertically reciprocating said cross-head, the male die *a* secured to said mandrel and the female die *b*² formed in the under side of the cross-head, substantially as described.

JOHN J. MULVANEY.
